(57) **CLAIM**

The ornamental design for a visor support, as shown and described.

DESCRIPTION

FIG. 1 is a top, rear, right side perspective view of a visor support showing a first embodiment of our new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a top, rear, right side perspective view of a second embodiment thereof; FIG. 9 is a front elevation view of FIG. 8; FIG. 10 is a rear elevation view of FIG. 8; FIG. 11 is a left side elevation view of FIG. 8; FIG. 12 is a right side elevation view of FIG. 8; FIG. 13 is a top plan view of FIG. 8; and, FIG. 14 is a bottom plan view of FIG. 8. The short dash-long dash broken lines in FIGS. 2, 7, 9, and 14 represent boundaries of the claimed design and form no part thereof. All other broken lines illustrate portions of the visor support that form no part of the claimed design.
